UNITED STATES PATENT OFFICE.

MARY DESHA, OF WASHINGTON, DISTRICT OF COLUMBIA.

DESIGN FOR A BADGE.

No. 38,193.

Specification for Design.

Patented Aug. 28, 1906.

Application filed June 28, 1906. Serial No. 323,905. Term of patent 3½ years.

To all whom it may concern:

Be it known that I, MARY DESHA, a citizen of the United States, residing at Washington, in the District of Columbia, and whose post-office address is 902 F street, (Box 72,) Washington, District of Columbia, have invented a new, original, and ornamental Design for a Badge, of which the following is a specification.

The drawing is an elevation showing my design.

I claim—

The ornamental design for a badge as shown.

MARY DESHA.
